F. H. Peelle, Inventor.

C. Snowdon.

UNITED STATES PATENT OFFICE.

FERNANDO H. PEELLE, OF JONESBOROUGH, INDIANA.

SUSPENDERS.

SPECIFICATION forming part of Letters Patent No. 644,631, dated March 6, 1900.

Application filed May 1, 1899. Serial No. 715,157. (No model.)

To all whom it may concern:

Be it known that I, FERNANDO H. PEELLE, a citizen of the United States, residing at Jonesborough, in the county of Grant and 5 State of Indiana, have invented a new and useful Suspenders, of which the following is a specification.

My invention relates to suspenders, and has for its object to provide an improved construction of yielding attaching-straps for the extremities of the shoulder-straps and for the back, and particularly to provide a simple and efficient construction of spring-actuated spools or drums, whereby the spring is completely housed and whereby its attachment to the spools is facilitated.

Further objects and advantages of this invention will appear in the following description, and the novel features thereof will be particularly pointed out in the appended claims, it being understood that the improvement is susceptible of various changes in the form, proportion, size, and minor details of construction without departing from the spirit 25 or sacrificing any of the advantages thereof.

To a full disclosure of the invention an embodiment thereof is shown in the accompanying drawings, wherein—

Figure 1 is a view of a pair of suspenders 30 provided with attaching-straps constructed in accordance with my invention. Fig. 2 is a transverse vertical section in detail of one of the attaching devices. Figs. 3 and 4 are inner face views, respectively, of the disks or 35 rotary members of the attaching device. Figs. 5 and 6 are central sectional views, respectively, of the same. Fig. 7 is a detail sectional elevation of the form of attaching device shown at the rear of the suspenders. Fig. 40 8 is a detail transverse section of the same.

Similar reference characters indicate corresponding parts in all the figures of the drawings.

In the illustrated embodiment of my invention, 1 represents the usual shoulder-straps, with the front portions of which are engaged the usual clasps 2, carrying the attaching-straps 3, which may terminate in loops 4 or other equivalent devices for engaging trousers-buttons. In the construction illustrated the clasp consists of a keeper 5, on which is mounted a clutch-arm 6, having a serrated or

toothed jaw 7 for engagement with the web of the shoulder-strap.

8 and 9 represent front and rear plates, of 55 which the former may be integral with the shank or arm 6, as shown, while the rear plate is attached by means of rivets 10 or the equivalents thereof to said shank. These plates are connected by a transverse pivot 11 in the 60 form of an eyelet, and mounted upon this pivot are parallel front and rear disks or drums 12 and 13, provided with peripheral strap-seats, in which operate the independent attaching-straps 3. Each disk is provided 65 with a flange which projects from the inner side of the disk toward the twin or companion disk, and on the outer surface of this flange is formed the above-mentioned seat for the attaching-strap. Furthermore, each disk 70 or drum is provided at and concentric with its central opening with a bearing-sleeve 14, which fits upon the pivot 11 and which is of a projection from the plane of the disk which is equal to that of the flange 15. The disk 75 12 is provided adjacent to its center or just outside of the sleeve-bearing 14 with a collar 16, which projects beyond the plane of the edges of the sleeve 14 and flange 15 and terminates approximately in the plane of the 80 inner surface of the disk 13, and the disk 13 is provided near its periphery or just within the circle formed by its flange 15 with a collar 17, which projects toward the disk 12, or in the opposite direction from that of the collar 16, to a point near the plane of the inner surface of said disk 12. Thus the disks, in addition to their central bearing upon the pivot 11, have a face-bearing upon each other in a plane midway between the body portions 90 of the disks and at the contacting surfaces of the sleeves 14 and flanges 15, and the disks are provided, respectively, with inner and outer concentric collars, which are of a width approximately equal to the interval between 95 the inner surfaces of the body portions of the disks, and said collars bound an annular chamber which is concentric with the axes of the disks. In this chamber is arranged the actuating-spring 18, provided with inner and outer terminal hooks 19 and 20 for engagement with the collars 16 and 17, said collars at suitable points being provided with transverse slots 16^a and 17^a. The hooks may be en-

gaged with the collars by sliding them transversely with relation to the collars in the operation of bringing the disks into operative relation, thus materially facilitating the assembling of the parts of the device. Furthermore, disengagement of the extremities of the spring from the collars is prevented by the fact that the spring is of a width approximately equal to the interval between the inner surfaces of the disks, while the collars are of a width sufficient to completely span the interval between the body portions of the disks.

A further advantage of the construction described resides in the fact that when one attaching-strap is held stationary the straining of the other will be resisted by the strength of the spring by which the disks are connected, whereas the straining of both straps simultaneously will rapidly and materially increase the tension of the spring, and thus will apply an increased resistance to the extension of the straps.

In Figs. 7 and 8 I have shown a slightly modified arrangement of parts wherein only one disk 21 is employed between the face-plates 22 and 23, said disk having a construction similar to that of the disk 13, in that it is provided with a bearing-sleeve and a flange 30 forming the seat for a running-strap 24. Projecting inward from the face-plate 22 is a collar 25, to which the inner end of the spring 26 is attached, the outer end of said spring being attached to the flange, which in the modified construction performs the function of the collar in the other form. The running-strap 24 is terminally attached to one of the face-plates and is traversed by a pulley 27, which supports the attaching-straps proper, 40. In this modified construction, as in the form shown in Figs. 1 to 6, inclusive, the spring is approximately equal to the width of the spring-chamber which is formed between the concentric inner and outer collars 45 carried, respectively, by the members of the

device, whereby lateral displacement of the spring or the terminal disengagement thereof from the members of the device is prevented.

Having described my invention, what I claim is—

1. In suspenders, the combination with the webbing or shoulder-strap, of parallel plates regularly spaced apart from each other, a disk rotatably mounted between the said plates and having inner and outer collars and a peripheral groove, a spring arranged in the intervals between said collars and attached thereto and held by the said disk between the plates, means for rotatably supporting the disk in the plates, and an attaching strap or cord having one end attached to the disk over which it is movable and the opposite end secured at one side to one of the plates.

2. In suspenders, the combination with a webbing or shoulder-strap, of parallel plates 65 equally spaced apart and connected at their upper portions, a pair of disks rotatably mounted between said plates, one of which has an outer flange with a peripheral groove, an adjacent collar, and a concentric sleeve, 70 and the other provided with a similar flange having a peripheral groove, a central sleeve and a collar adjacent the said sleeve and concentric therewith, the collars and sleeves of the opposite disks being fitted within and 75 bearing against each other, a spring arranged in the interval between said collars and attached respectively to the outer collar of one disk and the inner collar of the opposite disk, means for rotatably supporting said disks, 80 and attaching straps or cords movably engaging the grooved flanges of the disks and having their upper ends attached thereto.

In testimony that I claim the foregoing as my own I have hereto affixed my signature 85 in the presence of two witnesses.

FERNANDO H. PEELLE.
